(57) **CLAIM**

I claim the ornamental design for a wheelchair usage glove, as shown and described.

DESCRIPTION

FIG. 1 is a rear elevated view of a wheelchair usage glove showing my new design;

FIG. 2 is a front elevated view of the wheelchair usage glove;

FIG. 3 is a left side elevated view of the wheelchair usage glove;

FIG. 4 is a right side elevated view of the wheelchair usage glove;

FIG. 5 is a top plan view of the wheelchair usage glove; and, FIG. 6 is a bottom plan view of the wheelchair usage glove. The wheelchair usage glove shown in FIGS. 1-6 is for wear on the left hand. The wheelchair usage glove is understood to include an embodiment which is a mirror image of that shown, for wear on the right hand.
